METHOD AND MEANS FOR COLLECTING AND ARRANGING BISCUITS AND THE LIKE

Application filed December 28, 1929, Serial No. 417,307, and in Great Britain January 3, 1929.

This invention relates to devices for collecting and arranging biscuits or other articles of a shape or character susceptible of treatment according to the invention. For convenience in describing the invention the articles under treatment will be referred to as "biscuits".

The objection of the invention is to provide a machine adapted to receive biscuits delivered by a conveyor more or less continuously to collect them in an orderly manner and arrange them in a fashion suitable to their being handled in convenient batches.

According to the invention biscuits are received in single file, or in a plurality of files, and the machine arranges them in rows, one behind the other, by successively displacing a predetermined number or row of biscuits from the file or column in a direction transversely to the direction of movement of the file.

The invention also consists of means for passing a predetermined (row-forming) number of biscuits in file or column succession, arresting the head of the file for bringing the biscuits into close formation and for transverse displacement, holding the following part of the file in waiting for feeding as a subsequent row, whilst causing the first mentioned row-forming number of biscuits to be given a further movement in the feeding direction, thereby providing a clearance space between the last biscuit of the said number and the first biscuit of the detained file; then displacing the predetermined row transversely on to a batch plate which is given a movement, periodic or otherwise, to receive the biscuits row by row to constitute a close batch formation.

It is preferred to pass the biscuits by means of a narrow endless conveyor band which feeds the biscuits against a displaceable stop, and in front of the working face of a reciprocatory pusher that displaces the biscuits transversely to their previous direction of travel. Upon the arrival of the leading biscuit against the displaceable stop those biscuits of the file that lie outside the zone of action of the pusher are detained whilst the stop is taken away. The conveyor band

again advances the predetermined number of biscuits a short distance until they again encounter the stop. This short additional travel of the predetermined row separates it for transverse displacement from the main column. The pusher then displaces the row transversely to the direction of movement of the band on to a batch plate carried by a conveyor which is thereafter given a stepwise movement to accommodate the next row.

According to one convenient mode of hand manipulation of the machine a lever or arm, the reciprocation of which is adapted to give a stepwise movement of the plate, is provided with supplementary controls or handles one of which is adapted to supply a brake to the advancing column of biscuits while the other is adapted to adjust the displaceable stop backwardly.

In the drawings Fig. 1 is a diagrammatic plan view of the machine.

Fig. 2 is a part sectional plan view of the central portion of the machine.

Fig. 3 is a fragmentary perspective view showing the method of transferring from single file to a multiple row formation.

Fig. 4 is a diagrammatic view showing the relative positions of the pusher and gate at the end of a transfer stroke of the pusher.

Fig. 5 is an elevation of the machine, partly broken away, showing a side view of the single-file supply conveyor and an end view of the batch plate conveyor.

Fig. 6 is a top plan view, partly broken away, of the single-file conveyor.

Fig. 7 is a part sectional side view of the machine, broken away, showing the batch plate conveyor and control lever mechanism, the view being taken in the direction of the arrows, Fig. 2.

Fig. 8 is a side view of the mechanism for laterally adjusting the band wheel mechanism of Fig. 2.

Fig. 9 is a part sectional detail of the shiftable stop for the advancing end of the single file of biscuits.

Fig. 10 is a part sectional detail view in elevation, of the brake-actuating mechanism.

showing a modified arrangement of gate and plunger actuating mechanism.

Fig. 12 is a top plan view of the parts shown in Fig. 10.

In carrying the invention into effect as applied to collecting and arranging biscuits delivered in single file from a machine, for example, a biscuit creaming or sandwich forming machine as described in our co-pending application, Serial Number 325,194, filed December 11, 1928, the single file is received from the creaming machine and delivered by way of an inclined chute into a channel 1. The channel is formed by a fixed rail 2 and an adjustable rail 3 mounted upon a bottom member 4 which is pivoted at one end to the framework 5, the other end being connected in any suitable manner to the machine from which the biscuits are being collected. Lateral adjustment of rail 3 is effected by alignment screws 6 and thumb screws 7, or otherwise.

A bar 8 is located above the floor of the channel 1 a distance suitable to accommodate the thickness of the biscuits, giving sufficient clearance for them, but close enough to their tops to thwart any tendency of the column to buckle and prevent one biscuit riding over another. Bar 8 may be vertically adjustable 25 in its supports 9 and preferably extends the while length of channel 1. The bar is raised to an inoperative position when the apparatus is used to collect cream biscuits.

In the bottom of channel 1 is an endless traveling band 10 that carries the biscuits along the channel to the place where they are displaced transversely in the form of compact rows of predetermined length. For this purpose the band 10 extends across the machine and serves to feed the biscuits to the mechanism by which they are transferred in rows and assembled in batches.

A platform 11 for the displacement of the biscuits transversely is made of a thin plate, 45 which is spaced above the batch plates 12 that are ultimately to receive the biscuits.

The batch plates are carried on a batch conveyor 13 that preferably has a stepwise movement and advances at each step the width 50 of a biscuit row so that successive rows are arranged one behind the other in close order on the batch plate. The stepwise movement of the conveyor 13 may be produced by means of a ratchet 14 and pawl 15, the latter being actuated by a hand lever 16 which is suitably coupled to the pawl by a link 17.

A pusher 18 serves to feed the biscuits from the band 10 onto the batch plates 12 on conveyor 13. The pusher comprises a reciprocating frame having a vertical wall or working face 19. The pusher travels from a position of alignment with the fixed rail 2 of the channel 1 across to the delivery edge of platform 11. The length of the working face of the pusher corresponds with the length of a

biscuit row to be transferred. In front of the pusher face 19 and spaced therefrom a distance approximately equal to the internal cross sectional dimension of the channel 1 is a displaceable gate 20 mounted in such a way that when the pusher 18 is reciprocated to displace biscuits from the line of the file gate 20 moves out of the way and gives the biscuits a free passage across platform 11.

Reciprocatory movement is given the pusher by mechanism that also displaces the gate. The pusher and the gate are operatively connected to work synchronously with each other and with a hand lever 16 for slipping the batch plate conveyor. The mechanism chosen for illustration in Figs. 2, 5, 7 includes a rock shaft 21 mounted in brackets 22 on the frame of the machine. Rock shaft 21 is connected by lever 23 and link 24 to the hand lever 16.

A pair of levers 25, 25 are fixed to rock shaft 21 and links 26, 26 connect the levers to a pair of brackets 27, 27 on the pusher 18. When the rock shaft 21 oscillates the pusher 18 is reciprocated, sliding in its guides 28 and 29.

The brackets 27 in addition to serving as pivotal connections for links 26 carry a secondary rock shaft 30 from which a pair of arms 31 depend, carrying the gate 20.

The rock shafts 21 and 30 are coupled together by lever 32 and link 33 and arm 34 whereby any oscillatory movements of the rock shaft 21 will be communicated to the rock shaft 30, causing displacement of gate 20. The gate is mounted on the arms 31 by means of arms 35 and wing nuts 36.

To keep the biscuits from lifting while they are being transferred a rail 37 is secured to bracket 27 by means of a pair of light wire arms 38. The arms may be clamped in vertically adjusted position by means of wing nuts 39. Thus the arms 39 may have the necessary vertical and lateral adjustments.

A brake device in the form of a lateral blade 40 is arranged to restrain the movement of the file of biscuits along channel 1 and to accommodate the brake the rails 2, 3 of channel 1 terminate short of the near end of pusher 18. Brake blade 40 is mounted to swing on a spindle 41 which is oscillated by a finger 42 operated by a wire control 43 of known construction. The brake device is mounted on a member 44 which fits over the end of the adjustable rail 3 and is adjustable longitudinally thereof.

A transverse stop element 45 is provided near the end of the platform 11 and at the end of pusher 18 which is remote from the feeding side. This stop 45 is located to intercept the advance of the file of biscuits along the platform 11, although the band 10 continues to travel beneath the biscuits irrespective of their arrestment. The stop

45 is displaceably mounted upon guide member 28 for the pusher, and can be moved backward a predetermined distance. Such backward movement of the stop is effected by a wire control 46. If desired two separate stops may be used instead of the displaceable one, 45, here shown.

Upon removal or stepping back of stop 45 conveyor band 10 again acts upon the biscuits and moves them forward until they once more meet the stop in its reset position.

The Bowden or other suitable controls 43 and 46 that actuate the brake 40 and the stop 45 respectively may be conveniently actuated from the hand lever 16 by means of grip controls 47, 48. These grip controls are adjustable independently and the brake 40 is preferably arranged to operate before the position of the stop 45 is readjusted in the manner just described.

Varying width of batch plates may be accommodated in this machine and for that purpose pusher 18 is made with a central portion 18a having telescoping end pieces 18b, 18c connected by links 18d to a rotatable adjusting plate 18e which is slotted and provided with nuts 18f for locking the parts in their adjusted position. The guide members 28, 29 are also slotted for adjustment.

Band 10 is supported in guide wheels 49, 50, the latter being driven from a suitable source by a cone pulley 51. The band wheel is tensioned by adjusting screws 52 associated with the guide wheel 49. The band 10 can be laterally adjusted to accommodate different sizes of biscuit, with the consequent variation in the width of the channel 1. The shifting of the band is effected by axial adjustment of the spindle 53 of the guide wheel 49 by means of the forked double armed lever 54 which is given a pivotal movement by the screw spindle 55. The double armed lever 54 is fixed to shaft 56 extending beneath the machine. At the other end of the band a similar arrangement (not shown) may be provided, whereby lateral movements of both of the wheels are effected simultaneously.

In operation a single file of biscuits proceeding along the channel 1 travels onward after leaving the channel and proceeds across the platform 11 until it meets stop 45. Brake blade 40 is then actuated by pressure on the grip 47 to hold the foremost of the main biscuit column. As soon as the column has been arrested stop 45 is moved back the predetermined distance by actuating the grip 48 and the band 10 moves the predetermined number of biscuits that lies upon the platform forward until the foremost biscuit again meets the stop. This movement spaces the last biscuit of the row on the platform away from the foremost biscuit in the supply file. Thus is produced a working clear-

ance between the biscuits about to be moved transversely and the file of biscuits that is waiting in channel 1 ready to proceed across the platform when brake blade 40 is released.

When the predetermined row of biscuits has been thus selected and isolated from the file the pusher 18 is actuated by hand lever 16 to make a stroke transversely. Simultaneously with the stroke of the pusher the gate 20 is raised permitting the biscuits to be pushed out upon the leading edge of the batch plate 12 lying ready to receive them. The pusher and gate regain their initial position while the batch plate is being moved forward one step. Brake 40 is then liberated and stop 45 is returned to its normal position, by the spring return of the wire control 46. The waiting file is picked up by the traveling band and passed across the platform in front of the pusher for repetition of the transfer operations.

The cycle of operations is continued to build up a batch, row by row.

According to a modified embodiment of the invention (see Figs. 11 and 12) the pusher may comprise a bar 57 mounted upon a pair of guide rods 58 (only one of which is shown) and guided in bearings 59. The bar 57 carries an end plate 60 and a fixed central plate 61, the joints between which are covered by thin plates 62. The adjustable plate 60 and fixed central plate 61 together constitute the working face of the pusher. The adjustable end plate 60 is bent at right angles to form a support 63 for the adjustable stop 45a.

Adjustment of the end plate 60 is effected by a screwed rod 64 which engages nuts 65 carried by the pusher, the rod having a milled head 66 operating in a fork 67 mounted on the bar 57.

The gate 20a is carried by bent threaded rods 68 adjustably mounted on a rock shaft 69 pivoting in bearing 70 secured to the bar 57. The rock shaft has arms 71 fixed upon the ends thereof, said arms carrying rollers 72 engaging cam surfaces or ramps 73. On moving the pusher to displace a row of biscuits, the rollers 72 will ride up the ramps and cause the gate 20a to rise out of the way of the biscuits.

The bearings 70 have upwardly extending arms 74 supporting wires 75 to which a guard rail or wire 76 is attached, the wires 75 being secured by bolts 77 whereby the desired adjustments may be effected.

The pusher is reciprocated by a transverse shaft 78 seating in a forked member 79 secured to the guide rods 58, said shaft being pivotally mounted at its ends in levers 80 connected to the hand lever 16 by a link 81.

The appliance has been described as hand operated. However, it may be constructed to operate automatically in known manner, and the batch plates may be fed onto the conveyor 13 automatically.

The conveyor 13 may also be given automatic stepwise movement and may be timed so that an additional spacing interval is given between the addition of the final row of biscuits to one batch plate and the first row of biscuits for the next batch plate.

Such automatic features are not described in detail herein because the inventive novelty of my device is comprehended in the simple hand-actuated forms here shown.

Clearance, provided by the displaceable stop, between the last biscuit of a row and the first biscuit of the next succeeding row is important in biscuit handling, for it enables the predetermined row to be pushed off the band sidewise without catching on and breaking the adjacent edges of the next biscuit.

The stop has been described as being stepped back by means of the wire control, but the stated object may also be attained by a stop that is displaceable in any other way, and a second stationary or permanent stop may be spaced from the first stop by a distance equal to the clearance desired. The scope of certain of the claims, therefore, includes such equivalent modifications.

Having thus described our invention, what we claim and desire to secure by Letters Patent is:

1. In combination a continuous traveling band, a pusher parallel with said band and mounted for reciprocation crosswise the same, means for actuating said pusher, a displaceable stop positioned normally in the path of travel of articles carried by said band and arranged to be contacted by said articles at a place in front of the pusher, stop-actuating means, a brake member located in advance of the pusher and arranged to engage and arrest articles on the moving band before their arrival at the pusher, brake-actuating means, a conveyor beneath said band and arranged for stepwise movement in the direction of the forward travel of the pusher, a displaceable gate, a control lever, operative connections from said lever respectively to said pusher-actuating means, to said gate-actuating means and to said conveyor-actuating means, a pair of retractile grips associated with said lever, operating connections from one of said grips to said brake and from the other grip to the displaceable stop.

2. In combination a traveling band arranged for transporting biscuits in file formation, a stop removably positioned in the path of travel of the biscuits on the band, a brake adapted to engage a biscuit in said file remote from said stop, manually actuated means for operating said brake from a control station, manually actuated means for removing said stop and for relocating it slightly in advance of its original position, a pusher bar disposed lengthwise the conveyor at one side thereof beyond the brake, means for mov-

ing the pusher bar crosswise the band, a gate removably located along the edge of the belt opposite the pusher bar and operatively connected therewith so as to be lifted when the pusher bar moves across the band, a batch-conveyor belt located beneath the pusher bar, means for advancing the belt stepwise in a direction crosswise the band, batch plates carried by said belt, a control lever at said station operatively connected to said pusher bar and to said belt conveyor for actuating them simultaneously in opposite directions, said brake-actuating control and said stop actuating control both carried on said lever.

3. In combination, a continuous traveling band, a pusher parallel with said band and mounted for reciprocation crosswise the same, means for actuating said pusher, a brake member located in advance of the pusher and arranged to engage and arrest a column of articles on the moving band before their arrival at the pusher, brake-actuating means, a conveyor leading from the zone of operation of the pusher in the direction of movement of the pusher during its working stroke, actuating means for said conveyor, a displaceable stop located normally in the path of travel of articles carried by said band and positioned to be contacted by said articles at a place in front of the pusher, and means for displacing said stop away from the column of articles out of the path of the pusher, whereby before the operation of the pusher the column of articles beyond said brake can be carried on by the moving band and spaced from those held back by the brake.

In testimony whereof, we affix our signatures.

ROBERT F. MACFARLANE.
WILLIAM E. PRESCOTT.
